COMBINED PITCHER AND COVER THEREFOR

Earl S. Tupper, Smithfield, R. I.

Application October 19, 1956, Serial No. 43,421

Term of patent 14 years

(Cl. D44—21)

I claim:

The ornamental design for a combined pitcher and cover therefor, substantially as shown.
